Patented July 5, 1966

205,197

DISPLAY BOX FOR A DOLL OR THE LIKE

Joseph L. Bonanno, South Orange, N.J., assignor to De
Luxe Reading Corp., Elizabeth, N.J., a corporation of
New Jersey

Continuation of design application Ser. No. 79,430,
Apr. 9, 1964. This application June 21, 1965, Ser. No.
86,297

Term of patent 7 years

(Cl. D58—12.6)

FIG. 2

FIG. 1

FIG. 3

FIG. 4

FIG. 5

FIG. 7

FIG. 6

FIG. 1 is a front perspective view of a display box for a doll or the like, showing my new design;

FIG. 2 is a front elevational view thereof on an enlarged scale;

FIG. 3 is a top plan view thereof;

FIG. 4 is a rear elevational view thereof;

FIG. 5 is a side elevational view thereof;

FIG. 6 is a bottom plan view thereof; and

FIGS. 7 and 8 are fragmentary cross-sectional views along the lines 7-7 and 8-8 respectively of FIG. 4.

This application is a continuation of design application Serial No. 79,430, filed April 9, 1964 and now abandoned.

I claim:

The ornamental design for a display box for a doll or the like, substantially as shown and described.
